[57] CLAIM

The ornamental design for a chair, as shown and described.

DESCRIPTION

FIG. 1 is a left front perspective view of a chair showing my new design;

FIG. 2 is a front view thereof;

FIG. 3 is a rear view thereof;

FIG. 4 is a right side view thereof, the opposite side being substantially the mirror image thereof except for the absence of the adjustment lever shown underneath the seat; and,

FIG. 5 is a top view thereof.

1 Claim, 3 Drawing Sheets

FIG. 1
